US00D677563S

(12) **United States Design Patent**
Andre et al.

(10) **Patent No.:** **US D677,563 S**
(45) **Date of Patent:** **** Mar. 12, 2013**

(54) **PACKAGING**

(75) Inventors: **Bartley K. Andre**, Menlo Park, CA (US); **Daniel J. Coster**, San Francisco, CA (US); **Danielle De Iuliis**, San Francisco, CA (US); **Richard P. Howarth**, San Francisco, CA (US); **Jonathan P. Ive**, San Francisco, CA (US); **Steve Jobs**, Palo Alto, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Douglas B. Satzger**, Menlo Park, CA (US); **Calvin Q. Seid**, Palo Alto, CA (US); **Vincent Keane Seid**, legal representative, Los Gatos, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/406,057**

(22) Filed: **Nov. 9, 2011**

Related U.S. Application Data

(60) Continuation of application No. 29/384,961, filed on Feb. 7, 2011, now Pat. No. Des. 649,450, which is a continuation of application No. 29/363,450, filed on Jun. 9, 2010, now Pat. No. Des. 633,388, which is a continuation of application No. 29/340,508, filed on Jul. 20, 2009, now Pat. No. Des. 620,795, which is a division of application No. 29/281,505, filed on Jun. 25, 2007, now Pat. No. Des. 596,485.

Primary Examiner — Karen S Acker**(74) Attorney, Agent, or Firm** — Sterne, Kessler, Goldstein & Fox P.L.L.C.**CLAIM**

The ornamental design for packaging, as shown and described.

DESCRIPTION

FIG. 1 is a top perspective view of packaging showing our new design;

FIG. 2 is a top plan view thereof;

FIG. 3 is a bottom view thereof;

FIG. 4 is a front view thereof;

FIG. 5 is a rear view thereof;

FIG. 6 is side view thereof; and,

FIG. 7 is another side view thereof.

The broken lines in the Figures show portions of the packaging and environment which form no part of the claimed design. The dot-dash lines show unclaimed boundaries.

1 Claim, 5 Drawing Sheets
